ration of Delaware

Application September 20, 1932
Serial No. 633,974

16 Claims. (Cl. 302—50)

This invention relates to the conveying of pulverized or finely divided materials, such as portland cement, pulverized limestone, powdered coal, etc., which have the characteristic of becoming fluid when mixed with air under proper conditions. More particularly, the invention is concerned with a novel method and apparatus for conveying such materials through closed conduits or pipe lines, the invention affording es-
10 pecial advantages when employed in the conveying of materials which are supplied at rates which are variable or less than the maximum capacity of the system.

The method and apparatus of the invention 15 constitute an improvement on the conveying system of the Kinyon Patent No. 1,553,539, dated September 15, 1925, and on the apparatus disclosed in my co-pending application, Serial No. 612,616, filed May 20, 1932, the improved sys-
20 tem providing substantial economies in operation when used under the conditions above-men-
tioned.

The conveying system of the Kinyon patent, 25 which has now come into wide use, is characterized in that the material to be conveyed is supplied to a pump which contains an impeller screw, and the material is advanced into and through the transport line by the action of the screw. At the end of the screw, air is injected into the 30 material to render it fluent, and the material is caused to flow through the line by the mechanical action of the screw which is assisted to some extent by the expansion of the air. In order to prevent the injected air from flowing back into the 35 barrel of the pump and entering the material between the flights of the screw, a seal is provided by compacting the material between the end of the screw and the point of air injection. The Kinyon patent discloses various methods of 40 forming this seal, and in practice, it is common to use a screw of differential pitch, or to provide a substantial space between the end of the screw and the point of air injection, or to use a combination of these expedients. The effectiveness 45 of the seal required to prevent backward flow of the air varies considerably under different conditions of operation, and, in a specific system, care is taken to provide a seal which is of no greater effectiveness than is necessary, since the 50 use of a denser seal than is needed results in power losses and makes the system uneconomical to operate.

If the supply of material to the pump of a given system is to be constant throughout operation, 55 it is a simple matter to calculate in advance the

effectiveness of the seal required to prevent the rearward escape of air, even though the distance of conveyance varies during the normal operation of the system as, for example, by reason of the material being supplied selectively to a 60 number of receiving bins at different points along the pipe line. In such a system, a seal is provided which will resist the maximum back-pressure developed during conveying to the farthest point, and the power consumption in the motor 65 driving the pump is not excessive since a drop in back-pressure co-incident with delivery to an intermediate point decreases the reaction against the impeller screw and correspondingly reduces the power input to the motor.

But when such a conveying system is used to 70 transport material from storage silos, bins, hopper-bottom railroad cars, etc., the supply of the material to the conveyor is often erratic, since most pulverized materials tend to arch or bridge 75 across the discharge openings of the container or in the spouts leading to the hopper of the pump, and, when this occurs, the rate of supply of the material to the pump is likely to vary over wide ranges, usually less than full capacity. 80 Also, this condition obtains when the pump is used to convey the output of a number of grinding mills, the normal operation of which involves less than the full number being run continuously.

Under these conditions of variable supply at less than the full capacity of the system, it has been found necessary in practice with the equipment heretofore used, to increase the seal density considerably beyond that required for the full capacity of the conveyor. This is commonly achieved by employing a pump with a long barrel, using a screw having flights decreasing substantially in pitch toward the terminal flight, providing a dead space of extraordinary length 95 between the point of air admission and the terminal flight of the screw, and rotating the screw at a relatively high speed so that centrifugal force will supplement the effect of the other means to form a plug of material which prevents 100 the backward escape of air. The formation of the seal is also affected by the back-pressure of the remainder of the transport system and each of the elements mentioned involves substantial friction losses and adversely affects the power 105 input of the screw motor. In a system constructed and arranged in the manner described, the power losses become excessive and continuous when operation approaches normal and when an extremely dense seal is provided, the air in- 110

jected must be at relatively high pressure in order to break down the heavily compacted material and render it fluent. Also, air at high pressure is necessary to assist in reacting against the advancing material to form the seal and to permit the necessary volume of air to flow into the system.

Another difficulty encountered under conditions of variable supply of material in the use of the Kinyon system as heretofore constructed is that when the seal breaks, the material in the screw becomes aerated and cannot be effectively removed by the screw. If the seal is broken when the supply of material is at a minimum, the air in the pump barrel may under certain conditions offer enough resistance to prevent the material in the hopper from descending so that the seal can be reformed. As it is not customary to have an attendant present at the pump during the normal operation of the system, considerable volumes of air may be lost upon breaking of the seal and the condition of the pump may not be detected until a dust nuisance has been created or damage has been caused by the failure of delivery of material to equipment supplied by the conveying system.

It is obvious that under conditions of variable material supply, a Kinyon system as heretofore constructed is likely to be uneconomical in power consumption and breakage of the seal is liable to put the system out of operation. The poor economy in power consumption affects both the pump motor and the compressor equipment, the latter particularly, since the use of high air pressures greatly increases the cost of compressing the air, as the compressor power input increases rapidly, and the compressor efficiency decreases rapidly due to air slippage, as the pressure is raised.

The present invention is accordingly directed to the provision of a system operating on the Kinyon principle, which performs economically under the conditions mentioned, the new system using relatively low transport line and inlet pressures with a minimum differential between them under all conditions of variable material supply. The new system thus effects economies in power represented by compressor pressure and, to a lesser degree, in volume of compressed air, in input to the pump motor, because of the decreases in the force represented by back-pressure which the pump must overcome, and in the friction of the material advanced by the screw. Also, in the new system, an economy is effected by decreasing the air consumption of the system, the admission of air being controlled, if desired, in accordance both with the advance of material into the system and with the back-pressure of the system, the latter being indicative not only of the distance to which the material is conveyed in a system having intermediate delivery points but also of the actual volume of the material handled. Moreover, the new equipment has the decided advantage that interruption of the conveying operation due to breaking of the seal is avoided and the pump may have a relatively short barrel, which reduces friction losses.

The new system includes a pump of the characteristic Kinyon type and more particularly of the kind illustrated in Figs. 6 to 8 of the patent, the new pump also including a number of features disclosed in my co-pending application above-identified. This pump includes the usual barrel and impeller screw and at the end of the barrel

between the terminal flight of the screw and the point of air injection is mounted a flap valve adapted to close the end of the barrel. When the material is supplied to the pump in sufficient quantities, equal to the full capacity of the screw, the material discharged from the pump valve forces the flap valve to full open position in which it is without effect. However, when material is not supplied to the screw in sufficient quantities and does not fill the pump barrel completely, the flap valve tends to close, retarding the advance of the materials and causing them to accumulate in the seal space. In such a position, the valve supplements the effect of the other means employed for forming the seal and also decreases the effective opening of the valve through which the back-pressure of the system reacts. Since the effective barrel opening decreases with a decrease in the quantity of material advanced, the formation and maintenance of the seal is accomplished with a minimum friction loss under all conditions of supply of the material to the pump, thus affording a maximum power saving in normal full load operation.

Another advantage of the new system is that the pressure of the advancing material may be employed to control the admission of air used to create the initial fluent condition of the material in the system. Accordingly, the screw may be started before air is admitted rather than afterward and this simplifies starting and avoids losses in time and air. The control of the air by the material is provided by a mechanical connection between the flap valve and an air valve through which air flows into the material in an amount sufficient to provide the desired initial fluidity, the additional air necessary to render the variable quantity of material fluent to the degree required for conveyance being introduced into the material through a second valve as the material enters the transport line. The degree of opening of the second valve is controlled by the reaction of the back-pressure of the system and, since the back-pressure depends both on the volume of the material moving through the system as well as the distance to which the material is being conveyed, it is evident that by means of the valve responsive to back-pressure, it is possible to keep the air injected into the material to render it fluent at a minimum at all times.

In order to obtain the fullest economy resulting from the use of low air pressures as above-mentioned, it is preferable to operate the system with a minimum differential between the back-pressure and the supply pressure. Heretofore, the orifices through which air is supplied in a Kinyon pump have been carefully determined as to number and size of opening so that the line or back-pressure will not exceed approximately 40% of the inlet pressure, thus providing a factor of safety to avoid loss in air delivery even though loss of flow is negligible if the back-pressure does not exceed about 50%. My experiments indicate, however, that by using over-size inlet orifices, such that the total effective area of the orifices compensates for the loss of air at the given differential, it is possible to operate at a much lower pressure differential than has heretofore been used. For example, in a specific system in which the back-pressure is 10 pounds, it is possible by the use of such inlet orifices to maintain the necessary flow of air into the system by employing an inlet pressure of 12 pounds, and, similarly in a system which can be operated at a minimum

of 35 pounds back-pressure, a differential of 5 pounds is satisfactory.

For a better understanding of the invention, reference may be had to the accompanying drawings, in which:

Fig. 1 is a sectional elevation of the apparatus,

Fig. 2 is a detail elevation of the discharge end of the pump,

Fig. 3 is a cross-sectional elevation on line 3—3 of Fig. 4, and

Fig. 4 is a detail elevation on the side opposite to Fig. 2.

Referring now to the drawings, the pump illustrated comprises a hopper section 1, having a barrel section 2 of relatively short length opening into its front wall, and a screw shaft 3 passing longitudinally through the hopper and extending into the barrel section in concentric alignment with it. The screw shaft passes through the rear wall of the hopper and is supported for rotation in a unitary bearing support 4, beyond which it extends as at 5 for coupling to the usual prime mover (not shown). The hopper 1 and bearing assembly 4 are aligned on a common bed plate 6.

The barrel section is provided with a longitudinally movable barrel liner 7, having an external flange 8 complementary to the flange 9 of the barrel section. Secured to the flange 8 is the flange 10 of the valve body 11, the flanges 8, 9, and 10 being secured by through-bolts 12. The flights of the screw shaft, beginning with the flight 13, increase progressively in diameter to the opening into the barrel liner 7, for the purpose of withdrawing the material to be conveyed uniformly throughout the length of the hopper, as described more particularly in my application above-referred to. Within the barrel liner 7, the flights are of uniform diameter, clearing the inner wall of the liner by the usual $\frac{1}{2}$ " to $1/64$ ".

The pitch of the flights lying within the barrel liner 7 may decrease toward the terminal flight 14, but the decrease in pitch is preferably the minimum permissible to assist in forming the seal in accordance with the anticipated back-pressure condition. For average conveying distances, the pitch may approach actual uniformity, it being my preference to rely particularly upon the seal space beyond the terminal flight 14, as in the modifications shown in Figs. 6 to 8 of the Kinyon patent. To this end, the screw shaft 3, with its terminal flight 14, is arranged to extend into a cylindrical opening 15 in the valve body 11, this opening serving as an extension to the conduit formed in part by the barrel liner 7.

Air for increasing the mobility of the material advanced by the screw is admitted through a plurality of nozzles 16, arranged in an arc below the opening 15 into the valve body 11. In order to vary the relative distance between the air nozzles and the terminal flight of the screw to modify the seal density, substantially in the same manner as the plurality of series of air ports in the Kinyon patent referred to and particularly the modification above-described, the through-bolts

12 are provided with lock-nuts 17, whereby the relative spacing between the flanges 8 and 9 can be changed. In the position shown in Fig. 1, the minimum seal distance is indicated and it will be apparent that the forward adjustment of the flange and the parts connected to it will increase the effective seal distance.

A flap valve 18 closes the discharge end of the opening 15 into the valve body 11, this valve having a liner 19, of wear-resisting material, such as rubber or the alloy commonly known as "Stel-

lite". The valve is secured to the arm 20, which is keyed or otherwise fastened to the shaft 21, the latter extending through the side walls of the valve body 11, and arranged for partial rotation in it. This valve lies in the path of the material issuing from the pump barrel and when there is a full supply of material fed to the pump, the valve is forced to full open position. If the supply of material drops below the capacity of the pump, or is erratic, the valve tends to close and this causes the material to accumulate in the seal space between the valve seat and the terminal flights of the screw, thus causing the seal to be maintained under all conditions of supply. If desired, the valve may be weighted and for this purpose, one end of the shaft 21 is provided with a crank 22', upon which is mounted an adjustable counterweight 23', to modify the degree of reaction of the flap valve against the advancing material. At its discharge opening the valve body 11 terminates in a flange 22, to which is secured a flange of the remainder of the conduit or pipe line 23, which leads to the various delivery points.

The back-pressure of the system is indicated by an air pressure gauge 24, secured to a stand-pipe 25, which may conveniently be arranged as a part of the assembly of valve body 11, by connection to an opening 26 into the interior of the latter.

The operation of the pumping system as above specifically described, assuming that the automatic valve mechanisms to be described hereafter are not employed, is as follows:

The distance between the terminal flight 14 of the screw and the air nozzles 16 is adjusted so that the seal to be formed will be substantially in excess of that estimated for normal service in conveying at the maximum capacity of the pump to the longest conveying distance required. A full head or load of material is provided so that the flap valve 18 will be forced to its full open or inoperative position after the screw shaft 3 is started. Before the screw is started, compressed air is admitted through the nozzles in an excessive quantity and at the maximum pressure obtainable, or at least beyond the estimated operating pressure. The volume of air, as well as the pressure, is then decreased by the operator until the power input to the motor (not shown) driving the screw shaft begins to rise, which indicates that the proper degree of aeration is not taking place. The operator then raises the pressure and volume of air until the power required for the pump screw motor falls to a minimum stable condition. The seal density is then decreased by moving the flange 8 of the barrel liner 7 rearwardly, until a blow-back of air is noticed. The seal is then increased and maintained at the minimum position permissible by the back-pressure resulting from the resistance to the longest conveying distance at maximum capacity of the screw.

If the operator is unskilled, or electrical measuring instruments are not available, approximately the same results can be obtained by alternately and repeatedly adjusting the seal to the minimum distance to prevent the air from blowing back and decreasing the air pressure and volume to the minimum point at which the gauge 24 indicates a uniform and steady back-pressure. When this final adjustment is reached, the motor input, and air inlet pressure and volume are approximately at a minimum.

The feed of material to the pump hopper is

then decreased step by step and the operator which serves to permit a very small quantity of air to flow into the system, when heavy materials, having the characteristic of quickly losing their fluidity, are handled and the flow to the pump hopper stops completely for long intervals. 80
5 to retard the advance of material and cause it to accumulate and maintain the seal at a minimum density in combination with the remaining seal forming expedients. It will be understood that no change in the air pressure or volume condition will be made. Since the flap valve 18 not only resists the advance of material, but also restricts the effective opening into the valve body 11, the effect of back-pressure against the advance of material is such that a minimum seal 15 will be maintained from full to minimum load conditions.

It will thus be seen that a minimum power in compressed air and motor input is provided by the effect of the flap valve in supplementing 20 the other sealing devices, and this saving obtains throughout the entire capacity range of the system. If the flow of material stops entirely, the flap valve closes and functions as a simple check, but it has an additional function in conveying, since air under pressure is prevented from 25 passing backwardly and holding up the flow of material, or at least causing aeration in the barrel section, so that the seal cannot be reformed without the attention of an operator.

30 In order to effect further economies in operation, the supply of air to the nozzles is controlled by devices responsive to the position of the flap valve and to the back-pressure in the system, these devices including valves through which air 35 may be supplied to the nozzles and mechanism for operating them automatically.

The air from any suitable source is supplied 40 to the system through a main air line 27 which contains a cut-off valve 28 used to prevent air leakage when the system is shut down. A plug cock 29 in the line is employed to control the final pressure of the air and, when the cock is adjusted, it serves as an orifice plate. Beyond the 45 cock, a connection is made through a nipple 30 to a regulating valve 31 through which air is admitted to the nozzles in quantities proportional to the amount of material advanced by the screw, but in less amounts than are necessary for rendering the material sufficiently fluent so that 50 it can be transported to the nearest delivery point on the system. Air admitted to the nozzles through the valve 31 prevents initial discharge of unaerated material into the system, which would result in excessive back-pressure and over-load on the pump motor.

55 The valve 31 includes an inner cylindrical chamber 32, which communicates through a helical series of orifices 33 leading to a concentric outer chamber 34 which communicates through 60 the short nipple 35 with the air channel 36 through which the nozzles 16 are supplied. These nozzles have effective openings large enough to admit a volume of air considerably in excess of that required for aeration. The rate of air flow 65 through the valve is controlled by a vertically movable piston 37, provided with an orifice 38 to equalize pressures at its opposite ends. The piston is secured to a rod 39, which passes through a stuffing box 40 and is threaded for purposes 70 of adjustment and pivotally secured to links 41, pivoted at their upper ends to the crank 22, whereby movement of the flap valve 18 will control the position of the piston 37 and thereby 75 control the flow of air through the valve.

75 Valve 31 is provided with a needle valve 42,

which serves to permit a very small quantity of air to flow into the system, when heavy materials, having the characteristic of quickly losing their fluidity, are handled and the flow to the pump hopper stops completely for long intervals. 80
This valve may be adjusted so that this small quantity of air seeping through the material, particularly at elevations in the system or around bends, maintains the fluency, so that the motor will not be overloaded when material is again displaced into the system. A branch line 43 leads from the main line 27 between the valve 28 and the cock 29, this branch line containing a valve 44 and leading to the channel 36. When the system is to be shut down for an indefinite period, the branch line is employed for introducing air at full receiver pressure and volume to clear the transport line of material while the latter is in its aerated fluent condition. During this operation, the flap valve prevents the short-circuiting of air through the pump and the usual transport cut-off valve is not required. 90

Preferably at the side of the pump opposite to that on which valve 31 is mounted, air under the control of the cock 29 is admitted to the 100 back-pressure control valve 45, the additional air thus admitted being that necessary for completely fluidizing the material under all conditions of capacity and conveying distance. The air enters an inner cylindrical chamber 46, which communicates with the outer concentric chamber 47 through a relatively larger number of ports 48, arranged in a helix of upwardly decreasing pitch and uncovered serially by the piston 49. The piston is provided with an orifice 50 for purposes 105 of equalizing pressures, and is secured to a rod 51 which passes upwardly through stuffing boxes 52 and 53, where it is secured to a control piston 54 in cylinder 55. The control piston is subject to the reaction of back-pressure of the transport line system, the cylinder being in communication by a tube 56 with the stand-pipe 25 of the back-pressure gauge 24. The back-pressure acting against the under surface of the piston 54, causes the latter to rise against a coil spring 57 110 adjustable as to length by being threaded on the upper end of the piston, the tension of the spring being adjustable by set screw 58, secured to the spring retaining cap 59. As the piston 54 rises, it lifts piston 50, uncovering the ports successively and admitting an increasing amount of air to the channel 36 for injection into the material. The cylinder 55 is suitably vented, as at 60, to relieve pressure in the event of air slip-page beyond the piston 54. 115

In order to facilitate the starting of the system, a branch air line 61 (Fig. 2) under the control of cut-off valve 62 leads from the main line 27 into the hopper 1 below the barrel liner 7 and near the screw shaft 3. When the system has been shut down for a long time, the materials which have lain dormant in the hopper become packed together and when the system is started, the starting torque is excessive and greatly out 120 of proportion to the normal motor load. Under these conditions, the admission of air momentarily into the hopper renders the material in the hopper fluent and, when the material enters the screw barrel, the fluidity of the material 125 causes the screw to operate at low efficiency for a short period. This enables the pump motor to function without heavy overloads and permits the use of small driving motors, such as internal combustion engines of relatively small size. 130

Also, it permits small electric motors to be employed to avoid unfavorable power factors.

In the operation of the complete system, conveying is started by opening the main air supply valve 28 together with the plug cock 29. The back-pressure control valve is then adjusted so that it will function to admit air in excess of that which may be required to fluidize the material, although no air flows into the system at this time, since the flap valve is closed and there is no back-pressure to open the air valve which is responsive thereto. The operator then starts the pump motor, and as the advancing material displaces the flap valve from its seat, the piston 37 is lifted in proportion to the lifting of the flap valve and air is admitted at a sufficient rate to create the initial fluent condition of the material. Almost immediately, back-pressure reaction occurs, causing valve 45 to open to admit further quantities of air. The operator by reference to the line pressure gauge 24 now adjusts the spring 57 so that the minimum quantity of air is admitted responsive to back-pressure to create the necessary fluidity of the material for conveyance to the farthest discharge point of the system at the maximum capacity of the screw.

When the mechanism is adjusted in the manner described, it is set for all future operations since, as the back-pressure decreases because of a decrease in capacity or because of delivery of material to intermediate points, the air supply through the valve 45 is similarly decreased. The pressure and volume control of the air now having been established, the plug cock 29 is adjusted for full load conditions.

It will be apparent that in the new system, the control of the air afforded by the valve 45 responsive to back-pressure in cooperation with the flap valve 18 permits conveying with the seal of minimum density under less than full load conditions. This result is achieved because as the back-pressure decreases and the air supply decreases, the flap valve exposes a diminishing area of the material in the seal space to back-pressure and thus a seal of the least resistance for proper operation may be employed at all times with a consequent saving in power. Similarly, by using over-size air nozzles, the air pressures employed are much lower than those heretofore thought necessary and this effects a further economy of operation.

The new system functions on the Kinyon principle and in it the material is forced through the transport line by the mechanical action of the screw. The material is aerated as it leaves the screw and the action of the screw may to some extent be supplemented and assisted by the expansion of air. As the material leaves the transport line, it flows sluggishly and tends to seek a level. It retains this fluent condition until the air which has been injected into it has had an opportunity to escape. The system is, therefore, distinctly different in construction and operation from those systems in which the material is conveyed in suspension in air and a separator must be employed at the delivery point. Also, it operates on a distinctly different principle from that involved in those systems in which the material is forced through the line in the form of plugs.

What I claim is:

1. Apparatus for conveying pulverized materials, comprising the combination of a conduit, 75 a barrel section connected to the conduit, means

for advancing material through the barrel section and into and through the conduit, means for injecting compressed air into the conduit to aerate the material to be conveyed, the air being admitted beyond the advancing means to provide a space in the rear of the point of injection in which the materials will be compacted and form a seal resisting the rearward flow of air, and mechanical means in the seal space between the advancing means and the point of air admission for resisting the advance of material and assisting in causing the material to accumulate at sufficient density to form the seal. 80 85

2. Apparatus for conveying pulverized materials, comprising the combination of a conduit, 90 a barrel section connected to the conduit, means for advancing material through the barrel section, means for admitting compressed air to the conduit for aerating the material to be conveyed, the said means being disposed beyond the advancing means to provide a space in which the material will be compacted as they are advanced to form a seal resisting the rearward flow of air, and valve means in the seal space between the advancing means and the point of air admission, 100 said means resisting the advance of material and causing the latter to accumulate in said space at sufficient density to form the seal. 105

3. Apparatus for conveying pulverized material, comprising the combination of a conduit, 105 a receiving hopper, a barrel section connected to the conduit and to the hopper, a shaft supported for rotation within the hopper and barrel section and having screw flights for advancing material from the hopper into the barrel section, means for admitting compressed air to the conduit for increasing the mobility of the material to be conveyed, the said air being admitted at a point beyond the terminal flight of the screw so as to provide a space in said section in which 110 the material is compacted to form a seal resisting the rearward flow of air, and mechanical means between the terminal flight of the screw and the point of air admission for resisting the advance of material and compacting the latter. 115 120

4. Apparatus for conveying pulverized materials, comprising the combination of a conduit, a barrel section connected thereto, means for advancing material through the barrel section and conduit, means for admitting compressed air to the conduit for aerating the material being conveyed, said air being admitted a distance beyond the advancing means to provide a space in which the material will be compacted as it advances and form a seal resisting the rearward flow of air, and a flap valve in the seal space between the advancing means and the point of air admission for resisting the advance of material and causing the latter to accumulate in said space at sufficient density to form the 130 seal. 135

5. Apparatus for conveying pulverized materials, comprising the combination of a conduit, a barrel section connected thereto, means for advancing material through the barrel section and conduit, means for admitting compressed air to the conduit for aerating the material to be conveyed, the said air being admitted a distance beyond the advancing means to provide a space in which the material will be compacted as it advances and form a seal resisting the rearward flow of air, and a flap valve biased to close the barrel section against the advance of material, the valve being located in the seal 140 145 150

space between the material advancing means and the point of air admission.

6. Apparatus for conveying pulverized materials, comprising, the combination of a conduit, a receiving hopper, a barrel section between the hopper and conduit and connected thereto, a screw shaft arranged for rotation in the hopper and barrel section and provided with screw flights for advancing the material to be conveyed into and through the conduit, means for admitting compressed air into the conduit for fluidizing the material therein, said means being located beyond the terminal flight of the screw to provide a seal space through which the material advances, said material being compacted in said space and resisting the rearward flow of air, and a flap valve in the seal space between the terminal flight of the screw and the point of air admission, the valve being movable downwardly and biased to a position in which it closes the barrel section.

7. Apparatus for conveying pulverized material, comprising the combination of a conduit, a barrel section connected thereto, means for admitting material to be conveyed to the barrel section, means for injecting compressed air into the material in the conduit to increase the mobility of the material, and means responsive to the pressure of the material admitted for controlling the admission of air to the conduit.

8. Apparatus for conveying pulverized material, comprising the combination of a conduit, a barrel section connected to the conduit, means for admitting material to be conveyed to the barrel section and advancing it therethrough, means for injecting compressed air into the conduit beyond the material advancing means to increase the mobility of the material, a valve for controlling the supply of air to said means, and means in the conduit between the advancing means and the point of air admission responsive to the pressure of advancing material, the said means being operatively connected to the valve for controlling the opening of the latter.

9. Apparatus for conveying pulverized materials, comprising the combination of a conduit, a hopper, a barrel section between the hopper and conduit and connected thereto, a screw shaft supported for rotation in the hopper and barrel section for advancing materials therethrough, a flap valve tending to close the barrel section beyond the terminal flight of the screw shaft and movable by pressure of advancing material, means beyond the valve for admitting compressed air to the material to increase its mobility, a valve controlling the air supply, and means operatively connecting the first valve with the air valve to control the opening of the latter in accordance with the opening of the flap valve.

10. Apparatus for conveying pulverized materials comprising the combination of a conduit, a hopper, a barrel section, between the hopper and conduit and connected thereto, a screw shaft supported for rotation in the hopper and barrel section for advancing material therethrough, a flap valve tending to close the barrel section beyond the terminal flight of the screw shaft, the said valve being arranged for partial rotation with a supporting shaft, one end of the latter extending outside of the conduit and terminating in a crank, means for admitting air to the conduit beyond the flap valve, a valve for controlling the air supply valve, and a connection between said air valve and crank for controlling the supply of

air in accordance with the degree of opening of the flap valve.

11. Apparatus for conveying pulverized materials comprising means for admitting material to be conveyed to a conduit, means for admitting compressed air to the conduit to increase the mobility of the material and assist in its transportation through the remainder of the conduit, the said air admitting means including an air supply control valve, and means responsive to the back-pressure in the conduit for controlling the degree of opening of the valve.

12. Apparatus for conveying pulverized materials comprising means for admitting material to be conveyed to a conduit, means for admitting compressed air to the conduit to increase the mobility of the material and assist in its transportation through the remainder of the conduit, an air supply control valve, and means responsive to the back-pressure of the system for controlling the degree of opening of said valve, said means increasing the supply of air in proportion to increases in the back-pressure of the system.

13. Apparatus for conveying pulverized materials, comprising the combination of a conduit, a hopper for receiving material to be conveyed, a barrel section connecting the hopper and conduit, a screw shaft arranged for rotation in the hopper and barrel section for advancing material into and through the conduit, means for supplying compressed air to the conduit at a point beyond the terminal flight of the screw, a valve for controlling said air supply means, and means responsive to the back pressure in the remainder of the conduit operatively connected to the valve for controlling its degree of opening.

14. Apparatus for conveying pulverized materials, comprising the combination of a hopper, a barrel section opening into the hopper and forming a part of a conduit, a screw shaft arranged for rotation in the hopper and barrel section for advancing material therethrough, means for admitting compressed air to the conduit for increasing the mobility of the material, a valve for controlling the supply of air so admitted, means responsive to the back-pressure in the remainder of the conduit for controlling the degree of opening of the valve, and a flap valve between the terminal flight of the screw and the point of air admission to resist the advance of material and cause it to accumulate to form a seal and to restrict the effective surface area of the material exposed to the back-pressure of the system.

15. Apparatus for conveying pulverized materials, comprising the combination of a receiving hopper, a barrel section opening into the hopper and forming a part of a conduit, a screw shaft mounted for rotation in the hopper and barrel section to advance material therethrough, a flap valve in the conduit tending to close the barrel section and movable responsive to the pressure of advancing material, means for supplying compressed air to the conduit beyond the flap valve for increasing the mobility of the material, an air control valve for admitting a supply of air sufficient for the initial aeration of the material, said valve being operatively connected to the flap valve and controlling said air supply in proportion to the degree of opening of the flap valve, a second air supply control valve through which the air necessary to complete the aeration of the material is admitted, and means responsive to the back-pressure in the remainder of the conduit operatively connected to said second valve.

and controlling its degree of opening in proportion to the back-pressure.

16. Apparatus for conveying pulverized materials, comprising the combination of a receiving hopper, a barrel section opening into the hopper and forming a part of a conduit, a screw shaft mounted for rotation in the hopper and barrel section to advance material therethrough, a flap valve in the conduit tending to close the barrel section and movable responsive to the pressure of advancing material, means for supplying compressed air to the conduit beyond the flap valve for increasing the mobility of the material, an air control valve for admitting a supply of air

sufficient for the initial aeration of the material, said valve being operatively connected to the flap valve and controlling said air supply in proportion to the degree of opening of the flap valve, a second air supply control valve through which the air necessary to complete the aeration of the material is admitted, means responsive to the back-pressure in the remainder of the conduit operatively connected to said second valve and controlling its degree of opening in proportion to the back-pressure, and a manually operated valve for controlling the maximum volume and pressure of air supplied.
